UNITED STATES PATENT OFFICE.

GEORGE N. WOLFE, OF WASHINGTON, PENNSYLVANIA, ASSIGNOR TO SIDWAY-TOPLIFF COMPANY, OF WASHINGTON, PENNSYLVANIA.

DESIGN FOR A FRAME FOR A VELOCIPED.

Application filed June 30, 1927. Serial No. 22,626 Term of patent 14 years.

To all whom it may concern:

Be it known that I, GEORGE N. WOLFE, a citizen of the United States, residing at Washington, in the county of Washington and State of Pennsylvania, have invented a new, original, and ornamental Design for Frame for a Velocipede, of which the following is a specification, reference being

had to the accompanying drawing, forming part thereof.

The figure is a perspective view of a frame for a velocipede, showing my new design.

I claim:

The ornamental design for a frame for a velocipede, as shown.

GEO. N. WOLFE.
